UNITED STATES PATENT OFFICE

JOHN C. BOYTON, OF CLEVELAND, OHIO

WEATHER CAP

Application filed November 19, 1928. Serial No. 320,292.

This invention relates to weather caps for electrical lead-in conduits.

The general object of the invention is to provide a weather cap simple in construction, capable of easy assembly, yet affording full protection from the ingress of moisture or dirt.

Another object is to provide securing means for the cover piece which is permanently carried by one of the major elements of the assembly, does away with the necessity for handling small, loose parts, and avoids the alignment of the screws in threaded apertures at the time of assembling.

Another object is to provide a weather cap composed of only two simple castings which are inexpensive to manufacture and which, when assembled with insulator and screws in the manner hereinafter set forth, consists of only the two separable parts.

With these and other objects in view, the invention consists in the various novel features of construction and combination, all of which will be fully described hereinafter and pointed out in the appended claims.

In the accompanying drawings I have shown an embodiment of my invention, wherein Fig. 1 is an elevation of the weather cap assembled on the lead-in conduit; Fig. 2 is a sectional elevation of the weather cap; Fig. 3 is a bottom plan view of the weather cap showing the insulator block with conductor openings; Fig. 4 is a sectional view on line 4—4 of Fig. 2; Fig. 5 is a sectional view on line 5—5 of Fig. 2 and Fig. 6 is a fragmentary section on line 6—6 of Fig. 5.

Describing by reference characters the various parts of the embodiment illustrated in the accompanying drawings, 1 is the usual upright conduit extending from the elbow 2 which in turn connects with a conduit that extends through the wall or other building part through which the electric conductors 3 are to be passed.

To the upper end of the conduit 1 is attached the weather cap which is the subject of my invention and which consists of a body member 4 (screwed or otherwise secured, by known means, to the conduit 1) and a cover member 5, which fits over the upper edge of

the body member and extends over the insulator block 6 which is in turn securely fastened to the body 4.

The body member 4 is composed of the tubular portion 7, shown as interiorly threaded for the reception of the conduit 1, and having at its upper end a base 9 that is surrounded by an upwardly extending flange 10, and from the front of which project fingers 11. Extending upwardly from the flange 10 at opposite sides of the body member are lugs 12 which have threaded apertures to receive screws 14. The screws 14 after being passed through the lugs are upset as at 13 to prevent their removal or loss in shipment or handling, but still permitting longitudinal movement sufficient to effect the engagement or disengagement with the cover 5 as will be hereinafter described.

Extending inwardly at the top of the tubular portion 7 is a circular flange 15 which forms a shoulder 16 against which the conduit 1 may strike when the member 4 is secured thereto. The inner periphery of this flange 15 may be rounded as shown to present a smooth edge which will not cut or scrape the conductor insulation as it is drawn therethrough. At the junction of the fingers 11 with the base portion 9 is a reinforcing flange 9^a shown in Fig. 2, which also forms an abutment against which the insulator member 6 is held.

The insulator member 6 is composed of any suitable insulating material and is secured to the fingers 11 by fastening means 17, such as rivets. The insulator member 6 is provided with apertures 18 to receive the conductors 3. To accommodate a third wire, in case a three-phase circuit is used, the member 6 is provided with a knock-out opening 19 that is normally closed by a blank 20.

The cover member 5 is constructed to fit about the flange 10 with a front portion 21 extending down over the fingers 11 and over the insulator member 6 so as to substantially cover the same. To limit the downward movement of the cover over the body 4, the cover member is formed with a lug 22 which engages the upper edge of the flange 10.

At opposite sides of the cover 5, and match-

ing up with the screws 14 when the cover and body are assembled, are slots 23 to engage down over said screws at the lower edge of the cover and on opposite sides thereof are 5 outwardly extending flanges 24 which are cut by the slots 23 providing shoulders 25 to be engaged by the heads of the screws 14, when the same are screwed in thereby to prevent removal of the cover.

10 The weather cap as received by the electrician for installation consists as will be observed of only two separable parts; the body member 4 having the insulator 6 already secured thereto and screws irremovably screwed 15 into the lugs 12, and the cover member 5. No loose parts are present to slip from the hands of the electrician while assembling the cap on the job, nor is it necessary to align the screws 14 with threaded apertures in securing 20 the cover member 5 in place.

In assembling the cap, the body 4 is secured to the conduit 1, the conductors 3 threaded into place and connections made with the conductors from the conduit 1. The 25 screws 14 are backed out as far as necessary to allow the flanges 24 to pass and the cover member placed in position with the screws 14 entering the slots 23. The screws are tightened whereby the screw heads engage the 30 shoulders 25 and securely lock the cover in place.

Having thus described my invention, what I claim is:

1. A weather cap for electrical conduits 35 comprising a body member provided with means for attachment to a conduit, a cover for said body member adapted to fit over the upper edges thereof, locking means for said cover comprising laterally extending headed 40 bolt members on opposite sides of said body adapted for longitudinal movement, said cover being provided with laterally extending flanges on opposite sides thereof and slots extending from the edges of said cover 45 through said flanges providing shoulders adapted to be engaged by the heads of said bolt members when the cover is in place on the body to securely lock the same thereto.

2. A weather cap for electrical conduits 50 comprising a body member through which conductors are adapted to pass, a cover member having its lower edges extending over the upper edges of said body member, flanges on said cover, said cover being provided with 55 slots extending from the edges thereof through said flanges, headed bolt means on said body adapted to be received in the slots when the cover is in place, the heads of said bolt means adapted to engage over the flanges 60 to lock the cover in place.

In testimony whereof, I hereunto affix my signature.

JOHN C. BOYTON.
